UNITED STATES PATENT OFFICE.

GABRIEL FELSENTHAL, OF CHICAGO, ILLINOIS.

SAVINGS-BANK.

1,248,640.

Specification of Letters Patent.

Patented Dec. 4, 1917.

Application filed August 16, 1916. Serial No. 115,167.

To all whom it may concern:

Be it known that I, GABRIEL FELSENTHAL, a citizen of the United States, and resident of Chicago, county of Cook and State of Illinois, have invented certain new and useful Improvements in Savings-Banks, of which the following is a specification, and which are illustrated in the accompanying drawings, forming a part thereof.

10 The invention relates to devices commonly known as toy savings banks; its object being to secure simplicity of construction and operation with security against unauthorized opening, the invention consisting in a 15 structure such as is hereinafter described and as illustrated in the accompanying drawings showing a preferred embodiment, and in which

Figure 1 is a view in perspective of the device closed for use;

Fig. 2 is a sectional view on the line 2—2 of Fig. 1;

Fig. 3 is a sectional view on the line 3—3 of Fig. 1, the opening key being shown in 25 dotted lines;

Fig. 4 is a plan view of the body portion of the bank with the cover removed;

Fig. 5 is an inverted plan view of the cover;

30 Fig. 6 is a view in perspective of the opening key;

Fig. 7 is a view similar to Fig. 5, showing a slight modification; and

Fig. 8 is a view of a lining strip used in 35 the bank.

While the device is shown in pocket form, it may obviously be made of greater capacity. As illustrated the bank, designated as a whole by the numeral 10, takes the form 40 of a shallow circular box. The top and bottom are preferably provided with celluloid coverings 11, 12. The body 13 is cup-shaped, and may be drawn up from a single piece of sheet metal, the side wall being beaded at 45 its lower margin, as shown at 14, to receive a flat lining plate 15. The upper margin of the side wall of the body is flanged inward, as shown at 16. The cover 17 is similarly formed of a single sheet of metal flanged 50 downwardly at its margin, as shown at 18, to secure a lining plate 19, the margins of the celluloid cover being folded within the flange 18, as shown at 20, and secured by the plate 19.

55 The plate 19 is provided near its margin with a plurality of depending L-shaped lugs

21, as shown four in number, their ends being outwardly directed,—these lugs being formed by striking down portions of the metal. The flange 16 is provided with a 60 plurality of recesses, as 22, corresponding in number to the lugs 21 and adapted to permit the entry of the lugs when the cover or cap is applied to the body portion. A radially disposed spring tongue 23 is secured to the inner face of the plate 19, or, as shown at 24 in Fig. 7 may be formed integral therewith.

In applying the cover to the body portion this spring bears upon the flange 16 as the 70 lugs 21 enter the recesses 22. The cover being turned, the spring will fall into one of these recesses and thereby effectually lock the cover against unauthorized removal. Preferably the recesses 22 are so shaped that 75 the spring will enter but one of them, 25, this recess being deeper than the others and the length of the tongue being such that it will coöperate with this single recess only. An aperture 26 is formed in the side wall 13 80 of the body portion, in line with the recess 25.

A key 27, having its end 28 bent substantially at a right angle to its body portion, may be inserted within the aperture 26 and, 85 when tilted to bring its laterally extended end portion 28 in contact with the spring 23, the latter may be raised above the flange 16, whereupon the cover may be freely turned to bring the lugs 21 again into register with the recesses 22. A coin slot 29 is also formed in the side wall 13 to permit the insertion of a coin 30.

The wall 13 is lined with a strip 31 of resili- 95 ent material, celluloid being quite suitable for this purpose. This strip is provided at its ends with an interlocking tongue 32 and recess 33, and with a slit 34 which is located opposite the coin slot 29. The material is cut laterally at each end of the slit 34, pref- 100 erably by forming perforations 35, 36, in the strip. By this means a flexible lip 37 is provided for covering the coin slot, and will yield readily to the entering coin but will effectually seal the slot to prevent the discharge of a coin therethrough. The strip 31 also readily yields to the key 27, return- 105 ing to its normal position when the key is withdrawn.

Various changes in the device may be 110 made without departing from the scope of the invention, it being important only that

it be provided with an annular wall to which the cap or cover may be applied in the manner substantially as shown.

I claim as my invention—

- 5 1. A container having a cylindrical wall provided with a keyhole, and an instanding flange at its margin, such flange having a plurality of recesses one thereof being in axial alinement with the keyhole and differing in form from the other recesses, a cap for covering the end of the cylinder and having a plurality of axially projecting outwardly-facing L-shaped lugs adapted to pass through the flange recesses which are out of axial alinement with the keyhole as the cap is applied and to engage under the flange when the cap is turned, and a radially disposed spring catch carried by the cap and located between a pair of adjacent lugs and adapted to engage the flange recess in alinement with the keyhole when the cap is turned after application to the cylinder.
- 10 2. In a bank, in combination, a cylindrical closed body having a coin-receiving slot in its side wall and a lining of resilient material for the cylinder wall, such lining being slitted to form a flap for covering the coin slot.
- 15 3. In combination, a round box having a coin slot in its side wall, and a strip of elastic material loosely coiled in the box and urged against the wall thereof by its own elasticity, such strip having a flap covering the coin slot.
- 20 4. In combination, a round box having a coin slot in its side wall and a lining for

such side formed of resilient material covering the coin slot, and having a slit parallel with and adjacent thereto, such slit being laterally extended at its ends. 40

5. In combination, a round box having a coin slot in its side wall and a lining for such side formed of resilient material covering the coin slot and having a slit register 45 with the coin slot and being laterally extended in both directions at its ends.

6. In combination, a round box having a coin slot in its side wall, and a lining for such side formed of resilient material covering the coin slot and having round apertures, one adjacent each end of the coin slot, and a slit uniting such apertures. 50

7. In combination, a round box having a coin slot in its side wall, and a lining for 55 such side formed of resilient material covering the coin slot and having round apertures, one adjacent each end of the coin slot, and a slit uniting such apertures and in line with the centers thereof.

8. In combination, a round box having a coin slot in its side wall, and a strip of elastic material loosely coiled in the box and urged against the wall thereof by its own elasticity, such strip having a flap covering 60 the coin slot, the ends of the lining being interlocked.

9. A container for coin and the like having a receiving slot in one of its walls, a lining for such wall formed of resilient material slitted to form a yielding flap for 65 covering the receiving slot. 70

GABRIEL FELSENTHAL.
